(57) **CLAIM**

The ornamental design for an ophthalmic misting device, substantially as shown and described.

DESCRIPTION

FIG. 1 is a front perspective view of an ophthalmic misting device according to our new design;

FIG. 2 is a rear perspective view of the ophthalmic misting device shown in FIG. 1;

FIG. 3 is a front view of the ophthalmic misting device shown in FIG. 1;

FIG. 4 is a left side view of the ophthalmic misting device shown in FIG. 1, with the right side view being a mirror image thereof;

FIG. 5 is a rear view of the ophthalmic misting device shown in FIG. 1;

FIG. 6 is a top view of the ophthalmic misting device shown in FIG. 1; and,

FIG. 7 is a bottom view of the ophthalmic misting device shown in FIG. 1.

A characteristic feature of the design resides in the ophthalmic misting device having portions of different colors. This feature is illustrated by portions shown with a stippling pattern, and remaining portions shown without any stippling pattern. The portions with the stippling pattern and the remaining portions without any stippling pattern are different colors from each other. The drawing is not lined for color, and the design is not limited to any color or color combination. Shown in broken lines, the spacer bar does not form part of the design.
